UNITED STATES PATENT OFFICE.

HENRY C. DORN AND HERMAN A. LUEDKE, OF MILWAUKEE, WISCONSIN, ASSIGNEES TO
D & L MFG. CO., OF MILWAUKEE, WISCONSIN, A CORPORATION OF WISCONSIN.

BOTTLE-RECEPTACLE.

1,334,083.

Specification of Letters Patent. Patented Mar. 16, 1920.

Application filed May 3, 1918. Serial No. 232,345.

To all whom it may concern:

Be it known that we, HENRY C. DORN and HERMAN A. LUEDKE, citizens of the United States, and residents of Milwaukee, in the county of Milwaukee and State of Wisconsin, have invented new and useful Improvements in Bottle-Receptacles, of which the following is a description, reference being had to the accompanying drawings, which 10 are a part of this specification.

The invention relates to improvements in bottle receptacles more particularly adapted for containing milk bottles.

It is one of the objects of the present invention to provide a bottle receptacle in the form of an open box having means for holding the bottles in spaced relation with respect to each other.

A further object of the invention is to 20 provide a bottle receptacle in which the bottles are yieldingly supported in separated positions to eliminate liability of breaking during handling.

A further object of the invention is to 25 provide a bottle receptacle in which the bottles are supported and maintained in separated positions by rod and sheet metal parts forming part of the receptacle.

A further object of the invention is to 30 provide a bottle receptacle which may be easily kept in a sanitary condition.

A further object of the invention is to 35 provide a bottle receptacle which is of simple construction, is strong and durable, and is well adapted for the purpose described.

With the above and other objects in view 40 the invention consists of the improved bottle receptacle and its parts and combinations as set forth in the claims, and all equivalents thereof.

In the accompanying drawing in which the same reference characters indicate the same parts in all of the views:

Figure 1 is a top view of the improved 45 bottle receptacle, the bottle being indicated by dotted circles;

Fig. 2 is a longitudinal sectional view thereof taken on line 2-2 of Fig. 1; and

Fig. 3 is a transverse sectional view there- 50 of taken on line 3-3 of Fig. 1.

Referring to the drawing the numeral 5 indicates a wooden rectangular box like structure having thin side portions 6 and heavier end portions 7 which are nailed or 55 otherwise fastened together in any manner

desired. The lower corner edges of the receptacle are reinforced by lower angular channeled corner members 8 which are fastened to both the ends and sides of the box by rivets 9. The upper corner edge portions 60 of the box are also reinforced by upper angular reinforcing members 10 which are also connected to the box by rivets 11. The said upper reinforcing members 10 have inwardly offset and upwardly extending angular stacking projections 12 which are shaped to fit the lower reinforcing corner members 8 and hold the boxes in stacked relation.

The box or receptacle is divided into 70 bottle compartments 13 by upper and lower longitudinal partition rods 14 and 15, and upper transverse rods 16, and lower transverse partition plates 17. The longitudinal and transverse rods 14 and 16 are positioned 75 medially of the height of the box, and extend approximately in the same plane, and at the points of crossing each other are bent or crimped as indicated by the numeral 18 to form interlocking connections therebetween. 80

The lower edge portions 19 of the partition plates 17 are folded over to reinforce the same, and the end portions 20 of said partitions are bent at right angles for attachment to the sides of the box by rivets 21. 85

The ends of the partition rods 14 and 15 extend into the thick end members of the box as clearly shown in Fig. 2, whereas the ends of the partition rods 16 extend through the side members 6 of the box, and are riveted over washers 16' as clearly indicated in Fig. 3. The lower partition rods 15 extend through the partition plates, and at the points of connection are bent or crimped to form an interlocking connection therebetween as indicated by the numeral 21'. 95

Longitudinally extending rods 22 also extending through the partition plates and having crimped interlocking connections 23 therewith, and having their end portions also 100 embedded in the end members 7, serve as yielding bottom supports for the bottles.

It will be noted that some of the upper longitudinal and transverse rods are interwoven or extend alternately above and below 105 each other to form a more firm structure.

Bottles 24 indicated by dotted circles are positioned within the compartments and are yieldingly supported on the bottom rods and 110 spaced from one another by the longitudinal

and transverse rods and the partition plates so that the boxes can be roughly handled without liability of breaking the bottles.

The box ends are provided with elongated slots 25 for convenience in carrying the box.

In use the boxes or receptacles are made of a standard size and the partitions, rods and plates may be variably positioned to form compartments of different sizes so that 10 different boxes may be adapted to hold different sized bottles.

From the foregoing description it will be seen that the bottle receptacle is of very simple construction and is well adapted for 15 the purpose described.

What we claim as our invention is:

1. A bottle receptacle, comprising side and end members connected together to form a box-like structure with an open top and 20 bottom portion, spaced upper longitudinal and transverse rods having interlocking connections, spaced lower plates independent of said upper rods and rods extending therethrough and interlocked therewith, said rods 25 and plates forming upper and lower partitions to divide the receptacle into compartments, and rods positioned below the before mentioned rods and extending through the plates and having interlocking connections 30 therewith.

2. A bottle receptacle, comprising side and end members connected together to form a box-like structure with an open top and bottom portion, spaced upper longitudinal rods having medial crimped portions, spaced upper transverse rods having medial crimped portions which engage the crimped portions of the longitudinal rods and form an interlocking connection therewith, spaced 35 lower transverse plates independent of said upper rods and having means for connection with the sides of the box, spaced lower longitudinal rods extending through the plates and having crimped portions coacting with 40 the plates to form interlocking connections 45 therewith, said rods and plates forming upper and lower partitions to divide the receptacle into compartments, and longitudinal bottom rods positioned through the 50 plates to form bottom portions for said compartments, said bottom rods having crimped portions which form interlocking connections with said plates.

3. A bottle receptacle, comprising side 55 and end members connected together to form a box-like structure with an open top and bottom portion, spaced upper longitudinal rods having medial crimped portions, spaced upper transverse rods having medial crimped

portions which engage the crimped portions 60 of the longitudinal rods and form an interlocking connection therewith, spaced lower transverse plates independent of said upper rods and having lower reinforced edge portions and angular ends for connection with 65 the sides of the box, spaced lower longitudinal rods extending through the plates and having crimped portions which coact with the plates to form interlocking connections 70 therebetween, said rods and plates forming upper and lower partitions to divide the receptacle into compartments, and longitudinal bottom rods positioned below the before mentioned rods and extending through the plates to form bottom portions for said compartments, said bottom rods having crimped 75 portions which form interlocking connections with said plates.

4. A bottle receptacle, comprising side and end members connected together to form a box-like structure with an open top and bottom portion, reinforcing members engaging the upper and lower corner edge portions of the box, spaced upper longitudinal rods having medial crimped portions and 80 outer end portions which extend into the box ends, spaced upper transverse rods having medial crimped portions which engage the crimped portions of the longitudinal rods 85 and form an interlocking connection therewith, the ends of said transverse rods extending through the sides of the box and riveted, spaced lower transverse plates independent of said upper rods and having lower folded reinforced edge portions of double thickness 90 and bent ends for connection with the sides of the box, spaced lower longitudinal rods extending through the plates and having crimped portions which coact with the plates to form interlocking connections therebetween, the ends of said longitudinal rods extending into the ends of the box to form a connection therewith, said rods and plates forming upper and lower partitions to divide the receptacle into compartments, and 100 longitudinal bottom rods positioned below the beforementioned rods and extending through the plates to form bottom portions for said compartments, said bottom rods having crimped portions which rest upon 110 the folded portions and form interlocking connections with the said plates, the ends of said bottom rods extending into the ends of the boxes.

In testimony whereof, we affix our signatures.

HENRY C. DORN.
HERMAN A. LUEDKE.
